UNITED STATES PATENT OFFICE.

ISAAC UNGER, OF IRON MOUNTAIN, MICHIGAN.

COMBINATION TABLE AND AIR-MOISTENER DEVICE.

1,281,104.

Specification of Letters Patent.

Patented Oct. 8, 1918.

Application filed May 13, 1916. Serial No. 97,380.

To all whom it may concern:

Be it known that I, ISAAC UNGER, a citizen of the United States, residing at Iron Mountain, in the county of Dickinson and

5 State of Michigan, have invented a new and useful Improvement in Combination Table and Air-Moistener Devices, of which the following is a specification.

8 This invention relates particularly to devices adapted for use in connection with hot air registers, for imparting to the air the humidity which is desirable. As is quite generally understood, it is necessary that the air in a living-room, for instance, should 15 possess a rather high degree of humidity in order to give the best results. This is true from the standpoint of health, from the standpoint of comfort, and from the standpoint of economy. Thus, one is more comfortable, so far as warmth is concerned, in a properly moist atmosphere of 68° temperature than in a very dry atmosphere of 75° temperature. The economy of heating a residence, for illustration, is greatly improved by providing the air with a proper 20 degree of moisture, and at the same time the discomfort which arises from breathing dry air is obviated.

25 Notwithstanding the fact that the desirability of moistening the air is rather generally known, the people do not commonly avail themselves of this advantage, particularly in places which are heated by means of hot air, for the reason that desirable devices are not provided for use in connection with hot air registers.

30 The primary object of the present invention is to provide a useful article of furniture, of simple construction and capable of being cheaply manufactured, which may be used in connection with a hot air register to supply moisture to the atmosphere, and which may be at the same time employed as a table or taboret.

35 The invention is illustrated in its preferred embodiment in the accompanying drawing in which—

40 Figure 1 represents a combination table and air-moistening device constructed in accordance with my invention; Fig. 2 an end elevational view of a table embodying the invention, the construction being modified so as to be better adapted to a wall-register; Fig. 3, a sectional view taken as indicated at line 3 of Fig. 1; Fig. 4, a broken 45 sectional perspective view of one of the legs

of the table; Fig. 5, a broken perspective view of the socket or rim which supports the demountable evaporator-pan employed; Fig. 6, a broken perspective view, showing 60 one corner of a shelf or table employed; and Fig. 7, a broken perspective view, showing one corner of the evaporator-pan employed.

Referring to the construction illustrated in Figs. 1 and 3, A represents a floor provided with a hot air register 1; B, my improved combination table and air-moistener disposed over the register 1. The device B comprises four legs 2; a table-top 3 supported thereby; an intermediate shelf 4; 70 and an evaporator 5 supported by a rectangular rim or socket 6 secured to the legs a short distance above their lower ends.

The preferred manner of constructing the device is that illustrated. The legs 2 may be 75 either of wood or metal. The socket or rim 6 is securely attached to inwardly projecting lugs of sleeves or fittings 7 which are detachably and adjustably secured on the legs 2. The evaporator-pan 5 has an outwardly 80 turned flange α adapted to be supported on the horizontal flange 6 a of the rim or socket 6, which, as clearly appears from Fig. 5, is preferably of angular cross-section. The intermediate table or shelf 4 is preferably of 85 sheet-metal and detachably connected with lugs carried by adjustable and detachable sleeves or fittings 8 which are secured on the legs 2 at an intermediate point. The table-top 3 is secured to lugs of detachable 90 tubular members or fittings 9 applied to the upper ends of the legs 2. The upper ends of the members 9 are preferably closed, thus forming caps, as appears from Fig. 4. The fittings 9 are secured to the legs by set-screws 95 9 a . The sleeves 7 are split and equipped with clamping screws 7 a ; also, the sleeves 8 are split and equipped with clamping screws 8 a . The structure is thus of knock-down type; and the intermediate shelf and the 100 evaporator may be interchanged to provide a device adapted for use with a wall-register.

The table is of large enough base to rest upon the floor and clear the register 1, the evaporator-pan 5 being thus disposed just a 105 short distance above the hot air register. The pan 5 may be kept filled with water. When desired, it may be removed from the socket 6, for the purpose of cleansing.

In Fig. 2, B ^{1} represents a modification of 110 the device, adapting it for use in connection with a wall-register 1 a . In the modification,

the intermediate shelf and the evaporator are transposed, that is, a shelf 4^a is secured to the legs 2 a short distance above the floor; and the evaporator 5^a is demountably supported at an intermediate position. The table-top 3^a is applied to the upper end of the legs, as in the construction shown in Figs. 1 and 3. In this case, the hot air issuing from the register will pass largely beneath the pan 5^a, thus causing the water to evaporate freely.

The improved article of furniture not only provides for the moistening of the air in the room, but provides also a convenient support for books, periodicals, etc., which may be used by a person seated near the register. The device is self-contained and portable, being preferably equipped with casters. The economy of keeping a room comfortably warm is very greatly enhanced, and the discomfort and danger to health arising from breathing, while indoors, air which does not correspond

in humidity with the humidity in the external atmosphere is obviated.

The improved device can be manufactured cheaply and supplied to the public at a moderate price, thus encouraging the use of a device which should be in general use in houses or buildings heated by means of hot air.

The foregoing detailed description has been given for clearness of understanding only and no unnecessary limitation should be understood therefrom.

What I regard as new and desire to secure by Letters Patent is:—

An article of furniture comprising legs, fittings applied to the upper ends of said legs, a table-top supported by said fittings, fittings applied to the legs above the lower ends thereof, a socket-rim carried by said last-named fittings and an evaporator-pan removably carried by said socket-rim.

ISAAC UNGER.
